UNITED STATES PATENT OFFICE

135,077

DESIGN FOR BELTING OR THE LIKE FOR PERSONAL WEAR

Carl E. Ricketts, Rochester, N. Y., assignor to Hickok Manufacturing Company, Rochester,
N. Y., a corporation of New York

Application December 2, 1942, Serial No. 108,935

Term of patent 3½ years

To all whom it may concern:

Be it known that I, Carl E. Ricketts, a citizen of the United States, residing at Rochester, in the county of Monroe and State of New York, have invented a new, original, and ornamental Design for Belting or the like for Personal Wear, of which the following is a specification, reference being had to the accompanying drawing, forming part thereof, and in which the figure on the drawing is a plan view of a piece of belting or the like for personal wear showing my new design.

I claim:

The ornamental design for belting or the like for personal wear, as shown.

CARL E. RICKETTS.
